DESIGN FOR A FISH POLE HOLDER

George L. Curtis, Milwaukee, Wis.

Application September 10, 1945, Serial No. 121,982

Term of patent 3½ years

(Cl. D31—4)

To all whom it may concern:

Be it known that I, George L. Curtis, a citizen of the United States, residing at Milwaukee, in the county of Milwaukee and State of Wisconsin, have invented a new, original, and ornamental Design for Fish Pole Holders, of which the following is a specification, reference being had to the accompanying drawing, forming part thereof.

In the drawing:

Fig. 1 is a front elevational view of a fish pole holder showing my new design;

I claim:

The ornamental design for a fish pole holder, as shown.

GEORGE L. CURTIS.
